H. O. JOY & A. R. MONTFERRAND.
COMBINATION WASHING APPLIANCE AND BATH SEAT.
APPLICATION FILED NOV. 21, 1913.

1,103,516.

Patented July 14, 1914.

UNITED STATES PATENT OFFICE.

HARRY O. JOY AND ARTHUR R. MONTFERRAND, OF BOSTON, MASSACHUSETTS.

COMBINATION WASHING APPLIANCE AND BATH-SEAT.

1,103,516.

Specification of Letters Patent. Patented July 14, 1914.

Application filed November 21, 1913. Serial No. 802,293.

To all whom it may concern:

Be it known that we, HARRY O. Joy and ARTHUR R. MONTFERRAND, of Boston, in the county of Suffolk and State of Massachusetts, have invented certain new and useful Improvements in Combination Washing Appliances and Bath-Seats, of which the following is a specification.

This invention relates to a combination 10 washing appliance and bath seat adapted especially for use in apartments and houses having inconvenient set-tub facilities.

The object of the invention is to provide an appliance which is adapted to be supported upon a bath tub, comprising a frame 15 adapted to hold a pan or tub, and a wash-board hinged to said frame, the arrangement being such that the board may be swung up into position to enable clothes to 20 be rubbed thereon, or folded down upon the frame to form a bath seat, and when not in use the device may be hung up without occupying much space.

The invention will be readily understood 25 from an inspection of the accompanying drawing, in which—

Figure 1 is a sectional side elevation showing the wash-board swung up for use, Fig. 2 is a plan view of the same, and Fig. 3 is 30 a side elevation showing the board in position for use as a seat.

As illustrated in the drawing the device 35 comprises a frame composed of a pair of relatively long rods 10, 11 connected by a pair of relatively short rods 12, 13. The rods 10, 11 are curved at their ends, and preferably inclosed in short pieces of rubber tubing 14, said ends being curved to fit the roll 16 at the upper edge of a bath tub 18. 40 The rods 10, 11, and 12, 13 are spaced apart so as to form a substantially square frame which is adapted to engage the flange 20 of a pan or tub 22. This pan may be of any 45 convenient size and depth. We have found that a standard 15 inch pan is very satisfactory, and is one which can be readily replaced when required.

A wash-board 24 is mounted upon a board 50 or cover 26. This cover is preferably round-ed at its lower edge and provided with a pair of sheet metal bands or wear-resisting plates 28, which are adapted to bear against the rods 10, 11 when said board is in the position shown in Fig. 1. The board or cover

26 is hinged to the rod 13. As shown, a pair 55 of plates 30 are pivotally mounted at one end on the rod 13, and at their other end they are pivotally connected to the side cleats 32 of the cover. By reference to Fig. 1 it will be seen that the lower edge of the 60 cover 26 engages the plates 30 intermediate their ends and also engages the upper sides of the rods 10, 11, and is thus held in an inclined position so that a person standing beside the bath tub 18 can conveniently rub 65 clothes on the wash-board 20.

When the cover 26 is folded down into the position shown in Figs. 1 and 3, the appliance can be used as a bath seat for use in taking foot baths, and the like. When the 70 device is not in use, the pan 22 may be removed from the frame and hung up in a convenient place, and the cover 26 may be fastened to said frame by a catch 27 if desired. The frame and cover may then be 75 hung upon the wall, and it will be observed by reference to Fig. 3 that the appliance will project only slightly from the wall upon which it is hung, and will consequently 80 occupy only a small space.

From the description above set forth, it will be observed that the appliance is adapted for use in small apartments and houses where set-tub arrangements are inconvenient or lacking, and when not in use can be 85 stored in a small space.

What we claim is:

1. A combination washing appliance and bath seat, comprising a frame adapted to be supported upon a bath tub, a pan supported by said frame, a cover hinged to said frame, and a wash-board on said cover. 90

2. A combination washing appliance and bath seat, comprising a pair of rods having their ends bent and arranged to engage the roll at the upper edge of a bath tub, a pair of short rods connecting said first-mentioned rods, a receptacle removably supported by said rods, a cover hinged to one of said short rods, and a wash board mounted 100 on the under side of said cover.

3. A combination washing appliance and bath seat, comprising a frame having a pair of elongated members arranged to engage the upper edge of a bath tub, a pan removably supported by said frame, a cover, a pair of plates pivotally connected to said cover and to said frame and adapted to be 105

engaged by said cover intermediate their length to support said cover in an inclined position, and a wash-board on said cover.

4. A combination washing appliance and bath seat, comprising a frame arranged to engage the upper edge of a bath tub, a receptacle removably supported by said frame, a cover hinged to said frame, and a wash-board carried on the under side of said frame, said cover forming a seat when folded down on said frame but arranged to be

supported in an inclined position to enable said wash-board to be used with said receptacle.

In testimony whereof we have affixed our 15 signatures in the presence of two witnesses.

HARRY O. JOY.
ARTHUR R. MONTFERRAND.

Witnesses:

GEORGE CLARENDON HODGES,
CHAS. F. HOWE.
